(57) **CLAIM**

The ornamental design for a connection assembly for magnetic filter, as shown and described.

DESCRIPTION

FIG. 1 is a top perspective view of a connection assembly for a magnetic filter;

FIG. 2 is a bottom perspective view of the magnetic filter shown in FIG. 1;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines in the drawings depict portions of the connection assembly for magnetic filter that form no part of the claimed design. The dot dash dot broken lines in FIGS. 1-2, 5, and 7-8 depict the boundaries of the claim and form no part thereof.
